UNITED STATES PATENT OFFICE

HANS C. JORDEHOY, OF NORTH PLAINFIELD, NEW JERSEY, ASSIGNOR TO WOOD NEWS-PAPER MACHINERY CORPORATION, OF NEW YORK, N. Y., A CORPORATION OF VIRGINIA

FOLDER UNIT AND FORMER SUPPORT

Application filed May 28, 1927, Serial No. 194,914. Renewed December 11, 1929.

The principal object of this invention is to reduce the amount of framing required in an ordinary folder and especially in any folder that is laterally adjustable. I accomplish this by mounting each folder unit to permit the folder units to be moved bodily in a transverse direction, carrying with them the formers and associated parts, as nipping rolls, folding rolls, etc. Thus the adjustment for different widths of web can be provided for without auxiliary framing.

Other objects and advantages of the invention will appear hereinafter.

Reference is to be had to the accompanying drawings in which

Fig. 1 is a partly diagrammatic end view of a pair of folders and formers showing the frames in full and dotted lines located in two different positions for the folding of wide and narrow sheets;

Fig. 2 is a similar view showing the parts more in detail;

Fig. 3 is an end view;

Fig. 4 is a sectional view of a modification; and

Fig. 5 is an end view of the latter.

Newspaper presses are often equipped with two folding units placed directly under each of the two formers, each unit handling two pages of a four page wide web. The position of the folder unit is important, as care must be taken that the folding blade may not touch the web as it comes from the nipping rolls. In my previous application Serial No. 120,886, filed July 7, 1926, I have shown and described a unit folder which may be moved at will, laterally, to accomplish the purposes set forth in that case. The former and the carriage on which it is mounted are shown mounted in the conventional way on stationary frames. This requires almost the same amount of framing which is normally required for the conventional design of folder; namely, the frames which support the former carriage from the bed-plate. This invention relates to a similar arrangement of folder unit except that no auxiliary framing is required since the former carriage is mounted directly on the folder unit and moves therewith.

In Figs. 1, 2 and 3 I have shown folding units comprising frames 10, folding cylinders 11 and cutting cylinders 12 with the other usual features of folding units. These cooperate with the formers 13 forming rolls 14 and nipping rolls 15 as will be understood. These elements are mounted on an extension 10^a of the main frame. The usual drag roll is indicated at 22.

If narrow webs are being run, the folder frames 10 themselves are adjusted nearer together to the positions shown in dotted lines in Fig. 1 and in full lines in Fig. 2. In this case the webs run down through as indicated in Fig. 2.

In accordance with the present invention, the folder frames 10, each in a single unit, are placed on a bed plate 19 which may support several of them. The bottoms of all of the units are provided with finished surfaces and guideways resting on ways 18 on the bed plate 19. The bed plate is provided with fixed projections 20 through which adjusting screws 21 pass. Each adjusting screw is threaded into an opening in a frame 10.

For the purpose of cutting and folding a narrow web the frames 10 are moved inwardly as stated above with the extensions 10^a. The former nose is always in the center of the web independent of all adjustments. This avoids the possibility of the parts being set so that the web will enter into the folding couple at too great an angle from the side opposite the protruding blade and insures that the blade will clear the web, whether wide webs as indicated by dotted lines $\alpha\alpha$ or narrow webs as indicated by dotted lines α are being run. No other adjustment is necessary in this form. It also avoids the provision of any extra framing. The units can be adjusted exactly right for webs of intermediate widths.

The same parts are shown in the form illustrated in Figs. 4 and 5 and designated in the same way. Here, however, a former carriage 16 is mounted adjustably on the folder frame 10^a. Thus the former fold may be adjusted independently of the folder itself, thereby retaining all the advantages in an adjustable unit folder without having to

shift it every time it is desired to alter the former fold.

With this invention, I obtain the most advantageous arrangement of folders possible, at the same time permitting the most economical design of the machine, as the unit method of constructing machinery is acknowledged to be the most modern and practical method today.

10 Although I have illustrated and described only two forms of the invention, I am aware of the fact that other modifications can be made therein without departing from the scope of the invention as expressed in the 15 claims.

Therefore, I do not wish to be limited to all the details herein shown and described, but what I claim is:—

1. In a folder, the combination with a drag 20 roll and the former arranged for use with either a narrow or a wide web, of a folding machine frame having an extension supporting the former, and means for adjusting the frame of the folding machine with the former to register with the center of a wide or 25 narrow web on said drag roll.

2. In a folding mechanism, the combination 30 with a pair of formers and their forming and nipping rolls, adjustable to provide for feeding either a wide or a narrow web through each of them, of a pair of folding frames each having an upward extension on which the formers are carried, and means for adjusting said folding frames, with the formers, 35 laterally toward or from each other.

3. The combination with a folding machine 40 frame for supporting a folder, said frame being laterally adjustable, of a carriage adjustably mounted on said frame, forming and nipping rolls mounted on said carriage and adapted to be adjusted as a whole thereon for receiving a web, and means whereby said folding frame can be adjusted bodily carrying the carriage therewith.

45 4. In a folder, the combination with means for guiding either a narrow or a wide web and a former arranged to receive the web therefrom, of a folding machine frame supporting the former, and means for adjusting said frame with the former to register with the center of a wide or narrow web.

In testimony whereof I have hereunto affixed my signature.

HANS C. JORDHOY.
